LEAD PENCIL

Jacob Gordon, Washington, D. C.

Application September 14, 1940, Serial No. 356,839

6 Claims. (Cl. 120—17)

The invention relates to lead pencils of the general type in which the lead is fed from the pencil tip, as required, simply by sliding a manually operable member longitudinally of the pencil.

The principal object of the invention is to provide a pencil of the type set forth in which new and improved provision is made for feeding the lead from the pencil tip.

A further object is to provide a rather simple and inexpensive construction which may be easily manufactured and one which will be trouble-free.

With the foregoing and minor objects in view, the invention resides in the novel subject matter hereinafter described and claimed, description being accomplished by reference to the accompanying drawing.

Figure 1 is a central vertical longitudinal sectional view.

Figure 2 is a view similar to Figure 1 but at right angles thereto and showing a number of the parts in elevation.

Figure 3 is a perspective view showing the lead magazine and the means below the same for guiding and feeding the lead.

Figure 4 is a perspective view of the inner casing.

Figures 5 and 6 are transverse sectional views on lines 5—5 and 6—6 of Fig. 1.

A preferred construction has been disclosed and will be rather specifically described, with the understanding, however, that within the scope of the invention as claimed, variations may be made.

The pencil casing C consists of an inner tubular casing 7 and an outer tubular casing 8. The upper end of the inner casing 7 terminates below the upper end of the outer casing 8 to leave a space in which a sleeve 9 holding an eraser 10, may be inserted. It is preferable that said outer casing 8 be provided with one or more internal abutments 11 to contact with the upper extremity of the inner casing 7 to hold said inner casing normally against upward movement within said outer casing. The lower end of the inner casing 7 is provided with an end wall 12 having a central opening 13 through which a lead-guiding tube 14 passes, said tube being frictionally held or otherwise held in said opening. The lower end of the tube 14 projects downwardly to quite an extent from the casing end wall 12, and the upper end 15 of said tube 14 is enlarged and provided with a shoulder 16 which rests snugly on said end wall 12. A tapered cap 17 is provided to close the lower end of the outer casing 8 and to snugly receive the lower end of the lead-guiding tube 14, said cap 17 having an opening 18 through which the lowermost of the pieces of lead 19 extends.

For purposes to appear, the inner casing 7 is formed with an opening 20 near its lower end, with a longitudinal slot 21 extending from said opening to its upper extremity, and with a lateral notch 22 in one wall of said slot 21. The 5 outer casing 8 is also provided with a slot 23 which, when the two casings are assembled, communicates with the opening 20 and extends from the upper end of this opening to the lower extremity of the casing 8, the lower end of said 10 slot 23, however, being of course closed by the cap 17. This cap may be held on the casing 8 by friction, screw threads, or by any other suitable provision.

Within the upper portion of the inner casing 15 7, is a lead magazine 24 of tubular form, said magazine having a lateral stud 25 which is received in the notch 22 of the inner casing 7, after said magazine 24 is downwardly pushed into said casing and turned. The lower end of 20 the magazine 24 is equipped with a downwardly projecting lead-guiding tube 26, and the magazine bottom 27 declines to said tube to guide the pieces of lead 19 into the same from the magazine.

Slidable vertically in the inner casing 7 below the fixed tube 26, is a longitudinally split lead-guiding and feeding tube 27, said tube 27 having an enlarged head 28 at its upper end, which head 30 slidably contacts with the wall of the casing 7. 35 This head 28 is formed with an upwardly open socket 29 which receives the lower end of the fixed tube 26, the socket bottom 30 being normally spaced below the lower end of said tube 26, whereby the two may cooperate in limiting the 35 upward movement of the split tube 27, for a purpose hereinafter explained. The lower end of the split tube 27 is slidably received in the enlarged upper end 15 of the lead-guiding tube 14 previously described.

At opposite sides of its split, the tube 27 is provided with lateral lugs 31, and slightly below these lugs, a sleeve 32 slidably surrounds said tube 27, said sleeve being provided with upwardly projecting, rather blunt wedges 33 whose tips are 45 normally received between the lugs 31 at opposite sides of the tube split. A manually operable finger-piece 34 is provided at the exterior of the pencil, for operating the sleeve 32 to effect a lead feeding operation, said finger-piece being connected with the sleeve by means of a suitable spring 35 within the casing 7, and a shank 36 extending outwardly from the lower end of said spring to said finger-piece. This shank 36 passes through the opening 20 in the inner casing 7 and 55 through the slot 23 in the outer casing 8, and it is preferable to outwardly taper said shank as seen in Fig. 6, causing it to wedge normally into said slot 23, thereby preventing it from being accidentally moved. Upward sliding of the finger- 60

piece 34 will cause the sleeve 32, wedges 33 and lugs 31 to lift the split lead-feeding and guiding tube 27, until the socket bottom 30 strikes the lower end of the upper lead-guiding tube 26. 5 During this upward movement of the tube 27, any lead gripped by this tube is of course lifted with it. As soon as the ascent of the tube 27 is complete, however, further upward movement of the finger-piece 34 causes the wedges 33 to separate 10 the lugs 31, thereby expanding the tube 27 from gripping engagement with the lead and permitting the latter to again drop to its previous position. As soon as the finger-piece 34 is released, the tube 27 again contracts under its own 15 resiliency into gripping engagement with the lead, and during this contraction, the lugs 31 cam the blunt wedges 33 downwardly out of operative relation therewith. It will thus be seen that with the tube 27 elevated from its normal position and 20 engaged with the lead, that downward sliding of said tube 27 to said normal position, will feed the lead from the pencil tip. To so move said tube 27, I provide a coiled spring 37, the upper end of which bears against the lead magazine 24 and 25 the lower end of which abuts the head 28 of said tube 27.

The interior of tube 27 may of course be somewhat roughened if desired for better gripping engagement with the lead. Also, as the lower lead-guiding tube 14 must hold the lead against accidental upward sliding during use of the pencil, this tube 14 must be internally shaped in some adequate manner to effectively hold the lead. Any of the usual ways of accomplishing this will 30 suffice, such as slightly contracting the lower extremity of the tube 14, splitting said tube lengthwise to provide resilient fingers to grip the lead, or providing an internal tooth on said tube to bite slightly into the lead. 35 From the foregoing, taken in connection with the accompanying drawing, it will be seen that novel and advantageous provision has been made for carrying out the objects of the invention. Whenever, it is necessary to feed more lead to 40 the pencil tip, it is simply necessary to pull upwardly upon the finger-piece 34 and then release same. The thumb or one finger of the hand using the pencil may conveniently be used for this purpose. The necessary pressure against 45 the finger-piece 34 incident to sliding it upwardly, of course pushes said finger-piece inwardly to some extent, relieving the wedge-like 50 shank 36 from binding contact with the walls of the slot 23.

In assembling, all parts contained within the inner casing 7, are downwardly slid into said casing, the magazine 24 being then turned to seat the stud 25 in the notch 22, and the tube 27, sleeve 32 and finger-piece 34 being also turned to 55 move the shank 36 into the opening 20. The inner casing 7 and its contents are then upwardly slid into the outer casing 8, and the cap 17 is applied.

As excellent results may be obtained from the 60 details disclosed, they may well be followed. However, within the scope of the invention as claimed, variations may be made, as above stated.

I claim:

1. A lead pencil comprising a tubular casing 65 having a lead outlet at its lower end and lead-gripping means to prevent accidental sliding of the lead in said outlet, lead-guiding means in said casing extending downwardly to said outlet and including a vertically slidable longitudinally

split resilient tube, said split tube being self-contractible to normally grip the lead and being provided with lugs at opposite sides of its split, a sleeve slidably surrounding said split tube and having a finger-piece at the exterior of said casing by means of which it may be upwardly slid, said sleeve being provided with a wedge under said lugs to first lift said split tube as said sleeve is raised and to separate said lugs to expand said split tube when the latter reaches the limit of 10 its upward movement, and spring means for sliding said split tube downwardly when said finger-piece is released, said wedge being sufficiently blunt to permit said lugs to immediately cam it downwardly from operative relation therewith as 15 said split sleeve contracts upon release of said finger-piece, whereby said split sleeve will grip the lead as it is downwardly returned to its normal position by said spring means.

2. A structure as specified in claim 1; the upper end of said split tube being provided with a head slidably contacting with the casing wall, said head having an upwardly open socket, and a fixed lead-guiding tube in said casing having its lower end received in said socket and spaced 25 above the bottom thereof, the upward sliding of said split tube being limited by said socket bottom striking said lower end of said fixed tube.

3. A structure as specified in claim 1; together with a lead magazine secured in said casing and 30 having a fixed downwardly projecting lead discharging and guiding tube; the upper end of said split tube being provided with a head slidably contacting with the casing wall, said head having an upwardly open socket which receives the lower 35 end of said fixed tube, the bottom of said socket being downwardly spaced from said lower end of said fixed tube and coating therewith in limiting the upward sliding of said split tube.

4. A structure as specified in claim 1; together with an enlargement on the upper end of said split tube slidably contacting with the casing wall, and a fixed lead-guiding tube in said casing under said split tube, said fixed tube having an enlarged upper end in which the lower end of 45 said split tube is slidably received.

5. A structure as specified in claim 1; said sleeve being provided with a resilient arm carrying said finger-piece and having an outwardly tapered portion extending through a slot in the casing, said tapered portion being normally wedged in said slot to prevent accidental movement of said sleeve.

6. In a lead pencil, an inner tubular casing having a downwardly projecting lead-guiding tube, said inner casing having an opening near its lower end, a slot extending from said opening to its upper extremity, and a notch in one wall of said slot; means inserted downwardly into said inner casing for holding, guiding and feeding lengths of lead, said means including a lead magazine having a lateral stud received in said notch after downward passage through said slot, said means also including a manually operable lead-feeding member extending through said opening after downward passage through said slot; an outer tubular casing into which said inner casing is upwardly inserted, said outer casing having a downwardly open slot through which said manually operable member extends, and a hollow 70 pointed cap closing the lower end of said outer casing and receiving said downwardly projecting lead-guiding tube.

JACOB GORDON.
